UNITED STATES PATENT OFFICE.

CHARLES C. HARTUNG, OF ST. LOUIS, MISSOURI, ASSIGNOR TO EDWARD WALSH, JR., OF SAME PLACE.

DESIGN FOR SHEET-GLASS.

SPECIFICATION forming part of Design No. 22,343, dated April 11, 1893.

Application filed February 13, 1893. Serial No. 462,203. Term of patent 14 years.

To all whom it may concern:

Be it known that I, CHARLES C. HARTUNG, a citizen of the United States, residing at St. Louis, in the State of Missouri, have invented and produced a new and original Design for Sheet-Glass, of which the following is a full, clear, and exact description, reference being had to the accompanying drawings, forming a part of this specification, wherein the figures

o represent my new design, in which—

Figure 1 is a plan view of a sheet of glass ornamented with my design, and Fig. 2 is a cross sectional view.

The design consists essentially of the representation of different flowers in full bloom, so arranged as to appear on different planes to the eye, (the larger ones appearing to be the nearest) these being relieved by a bed or background of smaller flowers, as shown. To relieve the monotonous appearance of the rounded petaled blooms, I indisperse thereamong irregularly shaped sharp or pointed

petaled blossoms, which in some instances appear in a plane above the round petals of their companions, and overlap the same, while in others the reverse is the case. I also form as is shown in the drawings veins or ribs in the several petals of the blossom. By arranging the blossoms to make them appear in different planes, the larger ones are made prominent and retain their individuality, while the individuality of the smaller blooms is only perceptible where space will permit.

What I claim is—

The design for sheet glass, substantially as herein shown and described.

In testimony whereof I hereunto affix my signature, in presence of two witnesses, this 9th day of February, 1893.

CHARLES C. HARTUNG.
